(57) **CLAIM**

The ornamental design for a magnifier with an integrated mount, as shown and described.

DESCRIPTION

FIG. 1 is an isometric view of a magnifier with an integrated mount, showing our new design;

FIG. 2 is another isometric view of the magnifier with an integrated mount shown in FIG. 1;

FIG. 3 is a front elevational view of the magnifier with an integrated mount shown in FIG. 1;

FIG. 4 is a rear elevational view of the magnifier with an integrated mount shown in FIG. 1;

FIG. 5 is a right side elevational view of the magnifier with an integrated mount shown in FIG. 1;

FIG. 6 is a left side elevational view of the magnifier with an integrated mount shown in FIG. 1;

FIG. 7 is a top plan view of the magnifier with an integrated mount shown in FIG. 1;

FIG. 8 is a bottom plan view of the magnifier with an integrated mount shown in FIG. 1;

FIG. 9 is an isometric view of the magnifier with an integrated mount shown in FIG. 1, wherein the magnifier is shown in the stowed position;

FIG. 10 is another isometric view of the magnifier with an integrated mount shown in FIG. 9;

FIG. 11 is a front elevational view of the magnifier with an integrated mount shown in FIG. 9;

FIG. 12 is a rear elevational view of the magnifier with an integrated mount shown in FIG. 9;

FIG. 13 is a right side elevational view of the magnifier with an integrated mount shown in FIG. 9;

FIG. 14 is a left side elevational view of the magnifier with an integrated mount shown in FIG. 9;

FIG. 15 is a top plan view of the magnifier with an integrated mount shown in FIG. 9; and,

FIG. 16 is a bottom plan view of the magnifier with an integrated mount shown in FIG. 9.

The broken lines shown in the Figures are included for the purpose of illustrating portions of the magnifier with an integrated mount that form no part of the claimed design.
